(57) **CLAIM**

I claim the ornamental design for a scrub board for a wash bucket, as shown and described.

DESCRIPTION

FIG. 1 is a front isometric view of the scrub board for a wash bucket showing my new design.

FIG. 2 is a rear isometric view of the design of FIG. 1.

FIG. 3 is a right isometric view of the design of FIG. 1.

FIG. 4 is a left isometric view of the design of FIG. 1.

FIG. 5 is a front view of the design of FIG. 1.

FIG. 6 is a rear view of the design of FIG. 1.

FIG. 7 is a right side view of the design of FIG. 1.

FIG. 8 is a left side view of the design of FIG. 1.

FIG. 9 is a top view of the design of FIG. 1; and,

FIG. 10 is a bottom view of the design of FIG. 1.
